UNITED STATES PATENT OFFICE.

WILLIAM ARTHUR BURTON, OF SHEFFIELD, ENGLAND, ASSIGNOR TO WASHINGTON STEEL & ORDNANCE COMPANY, OF WASHINGTON, DISTRICT OF COLUMBIA, A CORPORATION OF WEST VIRGINIA.

CAP FOR ARMOR-PIERCING PROJECTILES.

1,097,528.

Specification of Letters Patent. Patented May 19, 1914.

Application filed February 10, 1914. Serial No. 817,869.

To all whom it may concern:

Be it known that I, WILLIAM ARTHUR BURTON, a subject of the King of Great Britain, residing at Sheffield, in the county 5 of Yorkshire, England, have invented certain new and useful Improvements in Caps for Armor-Piercing Projectiles; and I do hereby declare the following to be a full, clear, and exact description of the same, reference being had to the accompanying drawings, forming part of this specification, and to the figures and letters of reference marked thereon.

This invention has for its object to provide a cap for armor piercing projectiles 15 having the long contour best suited for flight and which shall be equally effective against armor plate at normal and at oblique impact.

20 In the accompanying drawings,—Figures 1 and 2 are sectional elevations of armor piercing projectiles with caps of known construction. Fig. 3 is a similar view showing the present invention.

25 Like letters of reference in the several figures indicate the same parts.

It has hitherto been found that in order 30 to obtain good results upon normal impact, there should be comparatively little metal in front of the point of the projectile, as shown in Fig. 2, in order that at the moment of impact the radial inertia of the cap material should be as great as possible. For oblique impact, however, which is the usual 35 condition in warfare, and more particularly when the angle of obliquity is great, caps constructed in accordance with the above principle are found to be comparatively ineffective and experience shows that it is necessary 40 to have considerable amount of cap material in front of the point of the projectile, shown in Fig. 1. On the other hand such a cap is ineffective at normal impact because the material in front of the point 45 of the projectile is set back upon impact, destroying the radial inertia and lateral support of the cap material surrounding the point of the projectile.

By the present invention I provide a cap 50 so constructed that there is considerable amount of metal in front of the point of the projectile as required for oblique impact but which is capable of moving back over the

head of the projectile without destroying the lateral support afforded by the rest of 55 the cap.

The invention is best described as follows: Fig. 3 of the drawing shows point A of armor piercing projectile surrounded and supported by a metal cap B secured thereto 60 by any preferred or ordinary means, such as the circular key H. The front portion of this metal cap is cut away as shown to form a conical recess C surrounding the point of the projectile. Resting on the very extreme 65 point is a ball of soft metal D of suitable dimensions and shape held in place by a windshield E, also of soft metal fixed to or integral with the main cap B as may be found convenient. 70

The action of this cap is as follows: Upon normal impact the windshield E and ball D are driven back and over the point of the projectile A until the rear surface of the ball D comes into contact with the front 75 surface of the cap proper B,—in so doing filling up the recess C and it will not be until the recess C is completely filled that the radial inertia of the cap B will be affected by the backward motion of the ball 80 D. At this stage the cap will function in the same way as a solid cap having the general shape shown in Fig. 2. On oblique impact the ball D will be thrown over to the side of the projectile which is farthest from 85 the plate and will, in so doing, form a cushion of soft metal on that side which will give support to the point of the projectile where it is most wanted and where the caps hitherto employed fail to give a sufficient 90 support. Further, the inertia of the main cap B will be unimpaired until the ball D is moved to the position where it is required to be to permit of the most efficient functioning of the cap as a whole. 95

Having thus described my invention, what I claim as new and desire to secure by Letters Patent of the United States, is:

1. An armor piercing shell embodying a pointed body, a cap surrounding the body 100 adjacent the point, and a ball of soft metal spaced from the cap and supported in line with the point of the body in position to be forced back around the point and into engagement with the cap by the impact of the 105 shell.

2. An armor piercing shell embodying a pointed body, a cap surrounding the body adjacent the point, and a ball of soft metal spaced from the cap and supported in contact and in line with the point of the body in position to be forced back around the point and into engagement with the cap by the impact of the shell. 25
3. An armor piercing shell embodying a pointed body, a cap surrounding the body adjacent the point and having a cavity therein around the point, and a ball of soft metal spaced from the cap and supported in line with the point of the body in position to be forced back around the point and into the cavity by the impact of the shell. 10
4. An armor piercing shell embodying a pointed body, a cap surrounding the body adjacent the point and having a cavity therein around the point, and a ball of soft metal spaced from the cap and supported in contact and in line with the point of the body in position to be forced back around the point and into the cavity by the impact of the shell. 15
5. An armor piercing projectile embodying a pointed body, a cap surrounding and secured thereto and having a cavity in its forward end around the extreme point of the body, and a ball of soft metal supported in line with the point and forward of the cap and adapted to be set back into the cavity by impact. 30
6. An armor piercing projectile embodying a pointed body, a chambered cap surrounding and secured thereto and having a cavity therein around the extreme point of the body, and a ball of soft metal supported in the chamber in line with the point and adapted to be forced back around the point and into the cavity by the impact of the shell. 35
